UNITED STATES PATENT OFFICE.

CHARLES S. CAMPBELL, OF NEW HAVEN, AND WILLIAM H. DAY, OF EAST HAVEN, CONNECTICUT, ASSIGNORS TO INDEX VISIBLE, INC., OF NEW HAVEN, CONNECTICUT.

INDEX OR FILE.

Application filed July 7, 1921. Serial No. 483,004.

To all whom it may concern:

Be it known that we, CHARLES S. CAMPBELL and WILLIAM H. DAY, citizens of the United States, residing in New Haven and East Haven, respectively, county of New Haven, State of Connecticut, have invented certain new and useful Improvements in Indexes or Files, of which the following is a full, clear, and exact description.

19 Our invention relates to indexes or files and, more particularly, to a device of this character in which a leaf or carrier is employed to carry or support a plurality of cards containing reference material. In the 15 particular embodiment shown a plurality of individually movable supporting members or carriers are used to support cards containing reference material. These carriers are of the general type shown in the patent 20 to Robert D. Hayes, No. 1,223,168, granted April 17, 1917, and the present invention in some aspects may be considered as an improvement upon the structure shown in that patent.

25 When the index or reference cards are mounted upon the swinging leaves or carriers and the carriers are manipulated to gain access to the cards on the various leaves, the outer edges of the cards may become slightly worn or soiled if the operator is careless in swinging the leaves, manipulating the cards, or otherwise handling the equipment.

One object of our invention is to obviate 35 the disadvantage above referred to and to provide a means to protect the outer edges of the reference cards.

Another object of our invention is to provide means for spacing and holding the 40 leaves apart so that the edge guards of one leaf will have no tendency to catch beneath the edge guards of the leaves on either side when the leaves are swung in use.

45 Another object of my invention is the provision of means for stiffening or reinforcing the edges of the leaves and particularly the front edges thereof.

To these and other ends, our invention 50 consists in the novel features and combinations of parts to be hereinafter described and claimed.

In the accompanying drawings:

Fig. 1 is a front elevational view of an index directory or file embodying our improvements;

Fig. 2 is a top plan view of the same;

Fig. 3 is an enlarged side elevational view of one of the leaves operatively mounted upon a support;

Fig. 4 is a sectional view on line 4—4 of Fig. 3;

Fig. 5 is a sectional view on line 5—5 of Fig. 4; and

Fig. 6 is a detail sectional view on line 65 6—6 of Fig. 4.

In order to illustrate the principles of our invention, we have shown at 10 a suitable supporting base which carries a guide member 11 having a guiding groove or 70 slideway 12 therein. Hung upon this member 11 are a plurality of leaves 13, each formed of a frame 14 consisting of a wire bent to form three sides of a substantial rectangle. The ends of this wire 14 are 75 extended at 15 and are provided with ball shaped members 16 which ride in the groove or slideway 11. Attached to this wire frame is a base plate 17, which, together with the wire frame, forms the supporting leaf 80 or carrier for the cards 18.

The record cards 18 shown in the drawings are of the type described in the patent to Irving Fisher No. 1,048,058, granted December 24, 1912, and are provided with integral tongues 19. The base plates 17 are provided upon one or both sides, as desired, with the guide members 20, with edge portions 21 which are spaced from the plate 17 and which are adapted to be engaged by the tongues 19 of the cards, to retain the latter in position. It will be apparent that the members 20 will not only serve as supporting members for the cards, but will serve as guide members also, along which 95 the cards may be moved at will. In the form shown, the members 20 upon opposite sides of the leaf are both attached thereto by the same securing means, i. e., by the rivets or eyelets 22.

At the outer edge of each leaf is secured a guard 23 which consists of a body portion 24 secured flatwise upon the plate 17 and flanged edge portion 25 which is turned over upon the body portion 24 to provide 100 a guard flange for the edges of the cards. 105

The part 25 is preferably sufficiently long to extend over the edges of the cards as clearly shown in Fig. 3, and will protect these edges and prevent the fingers of the operator from coming in contact therewith when manipulating the leaves.

At the upper and lower outer corners of each of the leaves is provided a spacing member 26, consisting of a piece of sheet metal shaped to form a hollow knob or body portion which spans the carrier or leaf and is bulged out upon each side of the same. These spacing members 26 are provided with ears 27 by which they may be secured to the plates 17 by rivets or eyelets 28. The body portions of these members, as clearly shown in Fig. 5, are bulged out on each side of the leaf so that they project to a slight degree past the flanges 25 and serve to protect these flanges against any deformity which might be caused by contact of two adjacent leaves. They also serve to space the leaves apart, as clearly shown in Fig. 2, so that they may be engaged by the fingers of the operator more readily, for manipulation. If such members are not provided, it also sometimes happens that when the leaves are swung back and forth upon each other, the rounded front edge of the flange of one leaf will enter and catch beneath the open edge of the guard flange of the adjacent leaf thus interfering with the manipulation of the equipment.

It will be apparent that the front edge of the base plate 17 will be greatly strengthened by the presence of these flanges or edge guards for the cards, so that there will be no tendency of the otherwise relatively thin edge to bend or warp out of shape. It is usual in the manufacture of these leaves to provide a hem upon the edge of the base plate, as shown at 30, but the strengthening effect of these flanges is an advantageous feature, in addition to this hem. It is, moreover, possible to omit the hem, if desired, when the flanges are used.

The guard flanges must be sufficiently deep, or in other words, the edge 25 must be sufficiently long, so that while the cards, when placed upon the leaf may be allowed sufficient movement toward the right hand or outer edge thereof, so that the tongues 19 can be slipped beneath the edge 21 of the guide to button the cards in position, still when the card is moved toward the left, as it will be after the tongue has been slipped under the guide, the right hand edge of the card will still lie beneath the flange, as clearly shown in Fig. 3.

Near the bottom of the carriers or leaves 13 suitable retaining clips or hooks 29 are secured to support from beneath the row or series of cards mounted upon the carrier. The bottom edges of the lower cards will be received between these clips and the plate

17, as clearly shown in Figs. 1 and 3, will thereby be prevented from slipping off the carriers.

While we have shown and described a preferred embodiment of our invention, it will be understood that the same is not limited thereto in all of its details, but is capable of many modifications and variations which fall within the spirit of the invention and within the scope of the appended claims.

What we claim is:—

1. In an index or file, a support for cards or the like, guard flanges upon one edge of the support to protect the edges of the cards, and spacing members secured on the support in alignment with the flanges.

2. In an index or file, a support, a plurality of leaves hinged to the support, having means thereon for supporting reference members, guard flanges on the outer edges of the leaves to protect the reference members, and spacing members secured to the edges of the leaves in alignment with said flanges to prevent the flange of one leaf engaging that of an adjacent leaf.

3. In an index or file, a support, a plurality of leaves hinged to the support, having means thereon for supporting reference members, guard flanges on the outer edges of the leaves to protect the reference members, and spacing members secured to the outer corners of the leaves in alignment with said flanges to prevent the flange of one leaf engaging that of an adjacent leaf.

4. In an index or file, a support, reference-carrying leaves hinged at one edge to the support, spacing members secured at the corners of the free edges of the leaves and projecting laterally therefrom both at the ends and at the sides of the leaves.

5. In an index or file, a support, reference-carrying leaves hinged at one edge to said support, and spacing members secured at the corners of the free edges of the leaves and embracing said corners to provide thick edges upon the leaves, both at the ends and sides thereof.

6. In an index or file, a support, a plurality of leaves hinged at one edge thereto and having means thereon for carrying reference members, a guard flange at the free edge of each leaf to protect said members, said flange terminating short of the ends of the leaf, and spacing members secured at the corners of the leaves in alignment with the guard flange.

7. In an index or file, a support, a plurality of leaves hinged at one edge thereto and having means thereon for carrying reference members, a guard flange at the free edge of each leaf to protect said members, said flange terminating short of the ends of the leaf, spacing members secured at the corners of the leaves in alignment with the guard flange, and common means for secur-

- ing said spacing members and said card flanges to the leaves.
8. In an index or file, a record-carrying leaf hinged at one edge thereof, relatively thick spacing members on the corners of the free edge of the leaf, and flanged guard members secured to the leaf adjacent said edge and extending between said spacing members. 65
- 10 9. In an index or file, a record-carrying leaf hinged at one edge thereof, relatively thick spacing members on the corners of the free edge of the leaf, and flanged guard members secured to the leaf adjacent said edge, extending between said spacing members and connected thereto. 70
- 10 10. In an index or file, a record-carrying leaf hinged at one edge thereof, relatively thick spacing members on the corners of the free edge of the leaf, flanged guard members secured to the leaf adjacent said edge and extending between said spacing members, and common means to secure said spacing members and said guard members to the leaf. 80
- 10 11. In an index or file, a record-carrying leaf hinged at one edge thereof, relatively thick spacing members on the corners of the free edge of the leaf, flanged guard members secured to the leaf adjacent said edge and extending between said spacing members and connected to the leaf coincidently therewith. 85
- 10 12. In an index or file, a support, a plurality of record-carrying members hinged thereto, each member comprising a base plate rectangular in shape, a frame extending on three sides of this plate, and means to connect the free ends of the frame, comprising a flanged guard member secured at the edge of the plate, and spacing members embracing the adjacent corners thereof. 95
- 10 13. In an index or file, a support, a plurality of reference-bearing members hinged thereto each comprising a plate, a frame extending along the hinged side of the plate and the two ends thereof, flanged guard members extending along the free edge of the plate, and spacing members at the adjacent corners, said spacing members and flange members being secured to the plate and to each other. 100
- 10 14. In an index or file, a support, a plurality of reference-bearing members hinged thereto each comprising a plate, a frame extending along the hinged side of the plate and the two ends thereof, flanged guard members extending along the free edge of the plate, and spacing members at the adjacent corners, said spacing members and flange members being secured to the plate and to each other, and said spacing members embracing the free ends of the frame. 105
15. In an index or file, a support, a plurality of reference-bearing members hinged thereto, each comprising a plate, a frame extending upon three sides of the plate including the hinged side, and reinforcing means secured along the fourth side of the plate and to the ends of the frame. 110
16. In an index or file, a support for cards or the like, guard flanges upon one edge of the support to protect the edges of the cards and spacing members at each end of said flanges in alignment therewith. 115
17. In an index or file, a support, a plurality of leaves hinged at one edge thereto and having means thereon for carrying reference members, a guard flange at the free edge of each leaf to protect said members, said flange terminating short of the ends of the leaf, and a leaf spacing member upon at least one corner of each leaf in alignment with the guard flange. 120
18. In an index or file, a record carrying leaf adapted to be hingedly supported at one edge thereof, spacing members on the corners of the free edge of the leaf, and a flanged guard member secured to the leaf adjacent said edge and between said spacing members. 125
19. In an index or file, a record carrying leaf adapted to be hingedly supported at one edge thereof, a spacing member on one of the corners of the free edge of the leaf, and a flanged guard member secured to the leaf adjacent said free edge and extending along said edge from said spacing member. 130
20. In an index or file, a support, a leaf hinged at one edge thereto and having means thereon for carrying reference members, a guard flange at the free edge of said leaf to protect said members, said flange terminating short of the edge of the leaf, and a bulged out sheet metal spacing member at one of the corners of the free edge of said leaf in alignment with the guard flange. 135
21. In an index or file, a record carrying leaf adapted to be swingably supported at one edge, spacing members on the corner of the free edge of the leaf, and a flanged guard member secured to the leaf adjacent said free edge and extending between said spacing members, said guard member and said spacing members being formed from sheet metal, said spacing members being bulged out to form a hollow knob. 140

In witness whereof, we have hereunto set our hands this 2nd day of July, 1921.

CHARLES S. CAMPBELL.

WILLIAM H. DAY.
